US00D480400S

(12) **United States Design Patent** (10) Patent No.: **US D480,400 S**
(45) Date of Patent: ** Oct. 7, 2003

(54) **ERGONOMIC ELECTRONIC INPUT DEVICE**

(75) Inventor: **P. Michael Leahy**, Colorado Springs, CO (US)

(73) Assignee: **Active Release Techniques LLC**, Colorado Springs, CO (US)

(**) Term: **14 Years**

(21) Appl. No.: **29/163,623**

(22) Filed: **Jul. 9, 2002**

(51) LOC (7) Cl. **14-02**

(52) U.S. Cl. **D14/412**

(57) **CLAIM**

The ornamental design for an ergonomic electronic input device, as shown and described.

DESCRIPTION

FIG. 1 is a front perspective view of a right handed ergonomic electronic input device showing my new design, including a scrolling wheel;

FIG. 2 is a rear perspective view of FIG. 1;

FIG. 3 is a left side elevational view of FIG. 1;

FIG. 4 is a right side elevational view of FIG. 1;

FIG. 5 is a front elevational view of FIG. 1;

FIG. 6 is a rear elevational view of FIG. 1;

FIG. 7 is a top plan view of FIG. 1;

FIG. 8 is a bottom plan of FIG. 1;

FIG. 9 is a front perspective view of a second embodiment of FIG. 1; including a trackball;

FIG. 10 is rear perspective view of FIG. 9;

FIG. 11 is a left side elevational view of FIG. 9;

FIG. 12 is a right side elevational view of FIG. 9;

FIG. 13 is a front elevational view of FIG. 9;

FIG. 14 is a rear elevational view of FIG. 9;

FIG. 15 is a top plan view of FIG. 9;

FIG. 16 is a bottom plan view of FIG. 9;

FIG. 17 is a bottom plan view of a third embodiment of FIG. 1, including a roller device;

FIG. 18 is a bottom plan view of a fourth embodiment of FIG. 1, including a hole for a laser light source;

FIG. 19 is a front perspective view of a fifth embodiment of FIG. 1 shown as a left handed device; and,

FIG. 20 is rear perspective view of a FIG. 19.
